(57) **CLAIM**

The ornamental design for a stop mount flange for an outdoor torch canister as shown and described.

DESCRIPTION

FIG. 1 is an upper perspective view of the stop mount flange for an outdoor torch canister showing my design; FIG. 2 is a lower perspective view thereof;

FIG. 3 is a front elevation view thereof, a back elevation view, a side elevation view, and an opposite side elevation view being identical to FIG. 3, shown with a top of a canister in broken lines;

FIG. 4 is an upper perspective view thereof, shown with a canister; and,

FIG. 5 is a front elevation view thereof, shown with a canister.

The broken lines showing the canister in FIGS. 3–5 are for the purpose of illustrating environmental structure and forms no part of the claimed design.
